(57) **CLAIM**

The ornamental design for power connector, as shown and described.

DESCRIPTION

FIG. 1 is a top end view of the power connector shown in FIG. 1;

FIG. 2 is a side view of the plug of the power connector shown in FIG. 1;

FIG. 3 is a top end view of the cavity for the plug of the power connector shown in FIG. 1;

FIG. 4 is another side view of the plug of the power connector shown in FIG. 1;

FIG. 5 is a further side view of the plug of the power connector shown in FIG. 1; and,

FIG. 6 is a yet another side view of the plug of the power connector shown in FIG. 1.

1 Claim, 3 Drawing SheetsFIG. 1

FIG. 3

FIG. 2

FIG. 5

FIG. 6
